UNITED STATES PATENT OFFICE

ROBERT M. SPURCK, OF LLANERCH, PENNSYLVANIA, ASSIGNOR TO GENERAL ELECTRIC COMPANY, A CORPORATION OF NEW YORK

ELECTRICAL CONDUCTOR STUD AND METHOD OF MAKING THE SAME

Application filed January 9, 1930. Serial No. 419,654.

My invention relates to electrical conductor studs and a method of making the same, and more particularly to conductor studs associated with electrical switch contact structure.

It is an object of my invention to provide an improved electrical conductor stud which shall be rugged and simple in construction, and have comparatively low effective electrical resistance to alternating currents.

It is a further object of my invention to provide a combined conductor stud and electrical switch contact so constructed as to substantially reduce the heat generated by current traversing the conductor stud and contact.

My invention will be more fully set forth in the following description referring to the accompanying drawing, and the features of novelty which characterize my invention will be pointed out with particularity in the claims annexed to and forming a part of this specification.

Referring to the drawing, Fig. 1 illustrates an elevational view, partly in section, of a conductor stud embodying my invention, and Fig. 2 is a cross-sectional view taken along the line 2—2 of Fig. 1.

In Fig. 1 of the drawing, there is illustrated by way of example, a conductor stud embodying my invention associated with switch contact structure. The conductor stud proper comprises a plurality of stranded copper conductors 1, arranged as in a bundle or cable and transposed so that the reactance of each individual circuit is approximately equal. As better illustrated in Fig. 2, each individual conductor is triangular in cross-section so as to form a sector of the cross section of the entire stud. It shall be understood, however, that the form of cross section of the individual conductors is immaterial and that a comparatively large number of conductors each having comparatively small cross section may be employed instead. Each conductor is preferably insulated from the adjacent conductors by a suitable insulating coating, such for example, as aluminum oxide.

The stranded conductors are also trans-

posed in a suitable manner, such as that illustrated, wherein the conductors are twisted with respect to the longitudinal axis of the stud, so that the eddy current effect of alternating currents is materially reduced. The manner of transposing the conductors to produce this result may obviously vary since stranded conductors of this type are well known.

For the purpose of eliminating heating at the union between the conductor stud and its terminal members, solid terminal members are integrally united, as by brazing or cold pressing, to the individual conductors at opposite ends of the stud so as to form a uniformly conducting part thereof. At one end of the stud a solid conducting member, as a cast copper sleeve 2, is fastened, as by brazing or by cold pressing as at 2', on to the individual conductors 1 so as to form a substantially integral part thereof, thereby eliminating high resistance unions between the stud and terminal member as is the case where clamping structures are employed. The terminal member 2 is screw-threaded externally, as at 3, so that it may be suitably connected to an associated conductor.

The stud at its opposite end has united thereto a solid conducting member 4, comprising in the present instance a stationary contact member adapted for fluid-break switching apparatus wherein the contact 4 is adapted to be engaged by a movable contact 5 within an insulating liquid such as oil. The terminal member 4 may be of material such as cast copper, and is united to the conductors 1 at 4' in the manner above described so as to form a substantially uniform conducting part thereof. An insulating bushing 6 of suitable character is mounted upon the conductor stud and is maintained in position by a nut and washer 7 and 8 coacting with the screw threaded surface 3 of the sleeve 2.

It shall be understood that it is within the scope of my invention to employ any suitable method of integrally uniting the solid terminal members to the individual conductors to form a uniformly conducting part thereof, and to arrange the individual con-

ductors in other ways than herein illustrated for the purpose of reducing the skin effect of alternating currents and thereby increasing the current carrying capacity of the stud.

5 What I claim as new and desire to secure by Letters Patent of the United States, is,—

10 1. An electrical conductor stud comprising a plurality of individually transposed conducting portions, means for insulating said portions from each other, and a solid conducting terminal member integrally united to each end of said conductor so as to form an integrally uniform conducting union between said transposed conducting portions and said terminal members.

15 2. An electrical conductor stud for carrying comparatively large currents comprising a plurality of stranded conducting portions insulated from each other, said portions being transposed so as to reduce skin effect of alternating currents traversing said stud, and a solid conducting terminal member integrally united to form a uniformly conducting part at each end of said stud.

20 3. In electrical switching apparatus of large current carrying capacity, an electrical conductor stud comprising a plurality of transposed conductors so arranged as to provide approximately equal reactance circuits through said stud, said transposed portions being insulated from each other, a conducting sleeve forming one terminal of said stud and integrally united thereto to form a solid uniformly conducting union, and a 25 solid conducting block forming a contact of said switching apparatus integrally united to the opposite end of said stud to form therewith a solid uniform conducting portion.

30 4. In electrical fluid-break switching apparatus for carrying comparatively large alternating currents, an electrical conductor stud associated with the contact structure of the switching apparatus comprising a plurality of stranded conductors transposed so as to increase the current carrying capacity of said stud, said conductors being insulated from each other, a cast conducting sleeve having a brazed union with one end of 35 said stud to form a terminal thereof, and a cast block having a brazed union with the opposite end of said stud to form a stationary contact of said switching apparatus.

40 5. A method of making an electrical conductor stud which comprises transposing a plurality of individual conductors so as to provide low effective resistance to alternating currents to form a main current carrying portion, and brazing a solid conducting member to each end of the stud.

45 6. A method of making an electrical conductor stud adapted to carry comparatively large currents, which comprises transposing a plurality of stranded conductors, 50 brazing a cast terminal member to one end

of said stud to form an integral uniform conducting union with said stranded conductor, and brazing a solid conducting member to the opposite end of said stud to form a contact member.

55 In witness whereof, I have hereunto set my hand this 6th day of January, 1930.

ROBERT M. SPURCK.
